UNITED STATES PATENT OFFICE.

GERALD DEAKIN, OF ANTWERP, BELGIUM, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed February 25, 1922. Serial No. 539,121.

To all whom it may concern:

Be it known that I, GERALD DEAKIN, a citizen of the United States, residing at Antwerp, Belgium, have invented certain new and useful Improvements in Telephone-Exchange Systems, of which the following is a full, clear, concise, and exact description.

This invention relates to telephone exchange systems and more especially to systems wherein automatic switching apparatus is employed for the extension of talking connections.

Where automatic switches, such as finder switches, are utilized for seizing and extending subscribers' lines either to succeeding selective switches or to operators' positions, a convenient way of handling calls incoming on the subscribers' lines is to divide said lines into groups and to assign the proper number of finder switches to serve each such group of lines. If the capacity of the automatic switches is sufficiently large it is advantageous to provide each switch with a plurality of sets of brushes, each set of brushes having access to a smaller group of lines. By this arrangement only the particular brush set having access to the group of lines containing the calling line need be taken for use.

In order to materially reduce the operating time it is proposed to divide each brush group into two sub-groups and to connect the lines to the terminal banks such, that one sub-group of lines appears as first choice lines to the brushes of half of the finders and as second choice lines to the brushes of the remaining finders. Likewise, the second sub-group of lines appears as first choice lines to the second half of the finder switches and as second choice lines to the first half of the finder switches. Normally, when a call originates in one of the sub-groups a switch having access as first choice to this sub-group is taken for use. Hence, the switch is only required to move over the first half of the group served by its brushes. When all finders having access to a sub-group as first choice are engaged at the time a call is originated in that sub-group, one of the finders having second choice access to this particular sub-group is set in operation to make connection with the calling line, provided one of these latter finders is idle at the time.

The selection of the set of brushes of an idle finder switch having access to the group of lines containing the calling line may be accomplished under the control of registers upon which the identity of the calling line 60 has been placed in response to the act of initiating a call. According to this plan the finder switch is operated directly in its brush selecting movement under the control of the registers. After the set of brushes 65 has been selected and rendered effective, the further movement of the switch, which may take place automatically, causes the set of brushes to make connection with the terminals of the calling line. 70

The object of the invention is to provide, in a system of the above described character where two groups of lines are respectively served by two groups of automatic switches as first choice, each group of lines being 75 served by the other group of switches as second choice, for directly operating any one of said automatic switches to make connection with a line.

A feature of the invention relates to the 80 provision of means for operating an automatic switch in either group directly in accordance with the identity of a calling line for making connection with such line. 85

A further feature relates to the provision of means for taking a record on register devices of the calling line identity and for directly operating an idle one of said automatic switches in either group in accordance with said record to make connection with the calling line. 90

A still further feature of the invention relates to the provision of an arrangement wherein an automatic switch in the group 95 serving a calling line as first choice is operated directly to select such line, and wherein if all switches of the group serving the calling line as first choice are busy an automatic switch in the other group is operated directly to choose the calling line. 100

Such other and further features as are contemplated by the present invention will become more apparent from a consideration of the following detailed description and 105 also from the appended claims.

Referring particularly to the drawing, Figs. 1, 2, 3 and 4, when arranged with Fig. 2 below Fig. 1, Fig. 3 below Fig. 2 and Fig. 4 to the right of Fig. 1, illustrate a portion 110

of a telephone exchange system embodying the principles of the present invention.

Fig. 1 shows one of a plurality of subscribers' lines terminating at the central office in the terminal bank of an automatic or line finder switch. This figure also shows the details of the automatic finder switch which, together with a second automatic switch hereinafter known as a cord selector switch, seen at the right of the figure, comprises one of a plurality of switching units serving to extend subscribers' lines to operators' positions.

Fig. 2 at the left of the left-hand vertical broken line shows a plurality of line relays arranged in groups, each relay being individual to a subscriber's line. Between the two vertical broken lines in this figure there are shown two allotter switches one for each of two different groups of finder switches and also certain common controlling equipment. To the right of the right-hand vertical broken line in Fig. 2 there is shown certain common devices for rendering the allotters ineffective in response to certain conditions among the groups of cords at the operators' positions.

Fig. 3 shows a portion of the register relays together with a part of a set of counting relays for controlling the directive movement of the automatic switches.

Fig. 4 shows one of a plurality of cord circuits which leads from the terminals of the cord selector switches shown in Fig. 1 and terminates in a plug at the operator's position. There is also shown the supervisory signals and controlling equipment individual to this cord. Moreover, this figure illustrates a common operator's selecting switch, the operator's talking equipment, and other devices at the position common to all cord circuits handled by that particular operator.

Fig. 5 is a schematic illustration showing how the subscribers' lines are divided into groups to appear in the banks of the line finder switches as first choice with respect to certain of the finders and as second choice with respect to other finders.

General description of the system and apparatus.

It is believed that a comprehensive understanding of the invention will be greatly facilitated by first giving a general layout of the system showing how the lines are divided into groups and in what manner they appear in the automatic switches at the central office, and also the method of allotting and operating these switches in response to the initiation of calls on the lines which they serve. While it is purely arbitrary, the assumption is made that the subscribers' lines are divided into groups of

200 lines each, a group of 200 lines appearing in the terminals of the finder switch at the central office, such as the switch 190, shown in Fig. 1, and also illustrated in Fig. 5. These finder switches are of the well-known rotary power driven type having a bank of 200 terminals arranged in ten different levels, there being twenty lines to a level. The ten sets of brushes, one for each level, are mounted on a brush carriage and are selectively chosen and tripped by means of a trip spindle mechanism so as to make contact with the terminals of the level when the brush carriage is rotated under the control of a power device. The structure of a switch of this character is illustrated in general in the patent to McBerty, 1,097,868, issued May 26, 1914.

In order to enable a desired number of simultaneous connections, a group of 200 lines will be provided with a suitable number of line finder switches at the central office. When one switch is busy and a call occurs in the group of 200 lines, another switch may be taken for use, and so on until all the switches are busy, at which time further calls will be obliged to wait until a switch becomes idle. Owing to the large capacity of the switch it is found that a considerable amount of time would be necessary for a set of brushes to hunt over an entire level of twenty terminals to choose a calling line. This hunting time is greatly reduced by a plan of division and distribution of lines about to be described. The total group of 200 lines may be divided into two groups of 100 lines each, meaning that each level of twenty lines in the finder bank (see Fig. 5) is divided into two halves. Each level, when thus divided, constitutes two separate groups of ten terminals each, the first ten terminals and the second ten terminals. In Fig. 5 the division is illustrated by the vertical broken line. In conformity with the division of each level of terminals into two subgroups of ten terminals each, the finder switches themselves are also divided into two groups. These will be referred to hereinafter and are designated in Fig. 5 as the A and B groups of finder switches. That is to say, half of the finder switches are segregated in one group and known as the A group of switches, one of which is shown in Fig. 5 at the left, while the other half of the finder switches, known as the B group, are similarly arranged. One of these switches is shown in Fig. 5 at the right. In correspondence with this method of dividing the finder switches up into two groups, the subscribers' lines served by these switches are also arranged in two different groups. The first 100 subscribers' lines, known as the A subgroup of lines, appear in the first half of the terminal bank of all the

A finder switches. For example, lines 500 and 501 are two of the A lines and are seen to appear in terminals 502 and 503 of the first half of the level of terminals served by the brush 504. The remaining eight lines of the A subgroup appearing in this level will be similarly connected. Furthermore, all the remaining lines of the 100 group of A lines will occur in the terminals of the other nine levels served by the A finders as first choice. In addition to appearing as first choice before all of the A finders the A lines, such as 500 and 501, are multiplied and appear in the terminals of all of the B finder switches. Their appearance in the B finder switches, however, is as a second choice. That is to say, they appear in the second ten terminals of the corresponding levels. The line 500 appears in terminals 505 and line 501 in terminals 506, both of which correspond to the terminals 502 and 503 of the A finders but are in the second half of the bank. These lines would be served by the brush 507 not as first choice but as second choice, brush 507 first traversing the entire set of ten terminals of the first half of the level before it can encounter the terminals of the lines 500 and 501 in the second half of the level.

In an analogous manner the remaining group of subscribers' lines, known as the B group, two of which are shown as lines 508 and 509, appear as first choice lines in all of the B finder switches and as second choice lines in all of the A finder switches. Lines 508 and 509 appear in terminals 510 and terminals 511 in the first half of the bank of all B finder switches, and are also multiplied to appear in terminals 512 and terminals 513 of the corresponding level but in the second half thereof with respect to the A line finder switches.

As will hereinafter be explained, the circuit arrangement is such that in the normal operation, whenever a call occurs on one of the lines of the A group, an idle one of the A finder switches normally serving said lines as first choice is started in operation to make connection with the calling line. Similarly, whenever a line occurring in the B group of subscribers' lines originates a call at a time when there is in the B group of finder switches an idle one, then this switch is set in operation to extend the calling subscriber's line. However, should one of the A subscribers' lines originate a call at a time when all of the A finder switches are busy, one of the B finder switches, if one be idle, is taken for use and operated to find the calling line in the A group. Conversely, the same is true with respect to the operation of an A finder switch to serve one of the B lines when the call is initiated when all of the B finders are busy but there is an idle one of the A finders.

Where each finder switch has a plurality of brushes one of these brushes, namely the one having access to the level of lines containing the calling line, must be selected and rendered effective. To accomplish this purpose there is provided a register mechanism consisting of a plurality of relays shown at the left in Fig. 3. These relays are responsive to the initiation of a call to set up a record identifying the particular level of terminals in which the calling line appears. That is to say, if the calling line is one belonging to the first level of finder switches then the relays 210 and 214 are energized and indicate that the calling line is one of the twenty lines occurring in the first level of terminals before all the switches. If the line originating the call appears in the second level then the register relays 211 and 215 are operated. If the calling line is one appearing in the third level the relays 212 and 216 are operated, and so on for each of the ten different levels of lines. The record having been established on the register relays the allotted line finder unit in the proper group is started in operation and is controlled directly by means of a controlling circuit and a set of counting relays shown in Fig. 3 in accordance with the identity of the line as recorded on the register relays. When the switch has operated in its brush tripping movement through a distance commensurate with the identity of the calling line, the controlling circuit is rendered ineffective and the operation ceases. Following the brush selecting operation the regular hunting movement of the switch occurs and the chosen set of brushes is caused to hunt over the terminals until the calling line is found, thereby extending the connection through to a cord selector switch 180 shown at the right of Fig. 1.

The cord selector switch, which is assumed to be a small rotary switch having a capacity of twenty sets of terminals, is started in movement and hunts over the terminals representing cords leading to the operator's position. When an idle cord is reached the cord selector switch stops and the calling line is thus extended through to the operator's cord circuit and she is given the proper notification as to the identity of the cord chosen.

The operator's equipment is connected to the chosen cord circuit, as illustrated in Fig. 4, by means of a selecting switch which is common to a number of cord circuits. After being connected to the cord circuit she may communicate with the calling subscriber to obtain the information necessary for her to complete the call or for extending it on to other operators.

The finder switches of the A group are allotted for use by means of an allotter

switch 201, which has a plurality of positions one for each of the different switches it controls. In a like manner the finder switches of the B group are allotted for use by means of the allotter switch 200. The allotter switches 201, 200 and the control switches 100, 300 and 220 are of the sequence switch type well-known in the art and corresponding in construction and operation to that shown in the patent to Reynolds and Baldwin, No. 1,127,808, issued February 9, 1915.

The cord selector switch 180 is a power driven device similar in principle to the finder switch 190, except that it is only equipped with a single set of brushes. The power magnet for operating the brush carriage of the switch 180 is indicated by the character 125.

20 *Detailed operation of the system.*

Initiation of a call in the A group of lines when one of the A finders is available.—It will be assumed that the subscriber of line 501, which occurs in the A group and in the third level of terminals in the finder switches, initiates a call at a time when some one of the A finder switches, normally serving this line as first choice, is idle. The subscriber, upon removing his receiver from the switchhook, completes a circuit from battery through the winding of line relay 205, outermost back contact of relay 112, over the loop of the calling line and returning by way of the middle contact of relay 112 to ground. The line relay 205 becomes energized and completes a path from battery through the winding of relay 112, right contact of relay 205 to the test terminal 151' of the subscriber's line in all the A and B finder switches serving said line. This potential applied to the test terminal serves as an identification of the calling condition of the line.

45 Furthermore, the line relay 205, on operating, completes a circuit traceable from battery through the make-before-break contacts at the outer armatures of register relays 214, 215, 216 and through corresponding contacts of all the remaining register relays not shown in this disclosure (the series circuit through the relays not shown being indicated schematically by the broken conductor), conductor 251, inner back contact of relay 216, winding of said relay, winding of relay 212, conductor 252, key 253, conductor 254, left contact of relay 205, key 255, left contact of relay 223, winding of relay 209, left back contact of relay 208 to ground. Relay 216 energizes in this circuit and its contacts are so arranged that its inner armature makes engagement with the front contact before the make-before-break contact at the outer armature is opened.

60 By this arrangement a circuit is immediately

closed which leads from battery, as above traced, through the make-before-break contacts of relays 214, 215, through the outer armature and contact of relay 216, winding of said relay, and thence through the windings of relays 212 and 209 to ground. Relays 212 and 209 also become energized in series with the relay 216.

65 Relay 216, upon energizing, opens the series circuit at its make-before-break contact such that if another line in any other level initiates a call the corresponding register relays 214, 215, etc., cannot be operated. That is, as soon as one line in the group of 200 lines succeeds in initiating a call, all other lines in the same group are barred from initiating calls until a switch is started to find the first calling line and the proper set of brushes tripped and the corresponding register relay released to restore the closed condition of the series circuit. This, of course, requires only a slight interval of time.

70 Relay 216, upon energizing, also completes a circuit from battery through the make-before-break contacts of relays 214 and 215, outer armature and front contact of relay 216, inner armature and front contact of said relay, conductor 256, windings of relays 219 and 221 to ground. These relays operate and serve to supply locking circuits for the counting relays, as will appear hereinafter.

75 Relay 209, which it will be remembered also energized in series with the register relays 216 and 212, at its left back contact 80 opens the energizing circuit of relay 208 whereby this latter relay is prevented from being energized so long as the relay 209 is operated. The relay 209 pertains to all the lines in the A group and is operated whenever one of these lines initiates a call for the purpose of starting the allotted A finder, as will presently be explained. Similarly, the relay 208 applies to the 100 lines of the 85 B group and serves for a like purpose. As 90 was mentioned above, whenever a line is calling the register relays prevent another line either in the same group or in the other group from effectively initiating a call until a set of brushes has been tripped serving the 95 first calling line. Should, however, two lines which appear in the same level one in the first half and the other in the second half, simultaneously initiate calls, the tendency 100 would be to start two line finder switches in 105 operation, one in the A group and the other in the B group, inasmuch as the same pair of register relays apply to both lines. This 110 is prevented by making the circuit of relay 209 on the one hand and the circuit of relay 208 on the other hand dependent respectively 115 upon the other relay.

120 When relay 209 is energized it also closes a circuit from ground through the right-hand contact of relay 212, conductor 257, 125

contact of 0' counting relay 258, winding of whereupon the stepping relay 218 is again stepping relay 218, right contact of relay 209, outer left back contact of relay 207, right contact of relay 223, lower right contact 235 of allotter sequence switch 201, closed in position 1, the lower right contact 108 (1), through the two windings in series of relay 101, lower left contact 116 (1), resistance 117 to battery. It is assumed that 5 position 1 of the allotter sequence switch 201 is the position in which this switch causes the allotment of the finder switch 190, shown in the drawing, and that the allotter switch is standing in position 1 at the time the call 10 under discussion is initiated. Relay 101 becomes energized and closes a circuit from ground through its front contact, upper right contact 122 (1), winding of sequence switch magnet 100 to battery. Sequence 15 switch 100 is driven out of position 1 and into position 2. In position 2 the relay 101 remains energized in the circuit traced and a circuit is also closed from ground through the front contact of said relay, lower right contact 107 (2), winding of the trip spindle 20 magnet 102 to battery. The magnet 102 serves to cause the rotation of the brush tripping spindle to select the set of brushes having access to the level of terminals 25 containing those of the calling subscriber's line 501.

The stepping relay 218, which was also energized in the fundamental circuit above traced, establishes a circuit from ground 30 through its contact, conductor 260, front contact of register relay 212, conductor 261, back contact of the No. 2' counting relay 262, winding of counting relay 263 to battery. Relay 263 operates and completes a circuit 35 from battery through its winding and the winding of relay 262, contact of relay 263, to ground at the inner left contact of relay 219. Relay 262, however, remains shunted and fails to operate as long as the stepping relay 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

The stepping relay 218, which was also energized in the fundamental circuit above traced, establishes a circuit from ground through its contact, conductor 260, front contact of register relay 212, conductor 261, back contact of the No. 2' counting relay 262, winding of counting relay 263 to battery. Relay 263 operates and completes a circuit from battery through its winding and the winding of relay 262, contact of relay 263, to ground at the inner left contact of relay 219. Relay 262, however, remains shunted and fails to operate as long as the stepping relay 218 is energized. As the tripping spindle passes each brush tripping position, the interrupter springs 104 and 105 make engagement with each other, and springs 103 and 104 engage each other as long as the tripping spindle is away from its normal position. At each closure of the springs 104 and 105 a circuit is completed from battery through the resistance 117, lower left contact 116 (2), windings of relay 101, upper left contact 108 (2), springs 105, 104 and 103 to ground. This circuit holds the relay 101 operated and shunts the stepping relay 218 in the fundamental circuit. At the first shunting of relay 218 it releases its armature and thereby opens the shunt around the winding of the No. 2' counting relay 262. Relay 262 operates and remains energized in series with relay 263. The tripping spindle continuing to rotate causes the springs 105 and 104 to open,

- (3+17) to ground. Relay 112 is operated in this circuit but the current flowing is insufficient to cause the actuation of the message register magnet 175. The cut-off relay 5 112 disconnects the line relay 205 from the calling line and locks in a circuit through its innermost front contact, and thence, as traced, through the winding of relay 101 to ground.
- 10 Relay 205, upon deenergizing, immediately opens the circuit which caused the energization of relays 209, 212 and 216, whereby these relays cannot again become energized as a result of this same call.
- 15 When the brush 151 first encounters the terminal 151' a circuit in parallel to the one traced through the right-hand winding of relay 101 is also closed and leads through the lower left contact 109 (3), brush 187, interrupter segment 118 to ground. As soon as the brushes 148, 149 and 151 are accurately centered upon the terminals of the calling line, brush 187 disengages the segment 118, the shunt is removed from around 20 the winding of relay 101 and this relay becomes energized in the circuit traced. Relay 101, at its back contact, opens the circuit of the power magnet 121 causing the brush carriage to cease its rotation. Relay 25 101, at its front contact, completes a circuit leading from upper right contact 122 (3), winding of sequence switch magnet 100 to battery. Sequence switch 100 leaves position 3 and moves into position 6. When the 30 sequence switch 100 reaches position 4 the circuit of the cut-off relay 112 is modified so that it now leads by way of terminal 151', brush 151, conductor 188, outer left contact of relay 132, outer left contact 133 35 (4+11½), resistance 134 to ground.
- 40 Furthermore, as sequence switch 100 reaches position 5 a circuit is closed from battery through the lower left winding of repeating coil 150, winding of relay 145, upper contact 146 (5+11), brush 149, over the loop of the calling subscriber's line 501 and returning by way of brush 148, contact 147 (4+11), upper left-hand winding of repeating coil 150 to ground. Relay 145 becomes 45 energized and a circuit is closed from battery through the winding of relay 158, inner right contact of relay 132, conductor 189, front contact of relay 145, left back contact of relay 140, resistance 144, upper contact 50 129 (5+11), inner left back contact of relay 132, lower right contact 128 (3+16) to ground. Relay 158 becomes operated in this circuit under the control of the supervisory relay 145, and at its left-hand contacts extends the talking conductors through to the brushes 159 and 160 of the cord selector switch 180. As soon as sequence switch 60 100 leaves position 5 it opens, at the left contact 131, the circuit of relay 101 and this latter relay becomes deenergized.

Upon the arrival of sequence switch 100 in position 6 a circuit condition is prepared for the operation of the cord selector switch 180 to extend the calling line over an idle cord circuit to the operator's position. One of these cord circuits is shown in Fig. 4. The power magnet 125 for rotating the brushes of the cord selector switch is operated in a circuit from battery through the winding of said magnet, lower right contact 75 119 (6), back contact of relay 101 to ground. The brushes 159, 160, 161 and 162 are rotated from one set of terminals to another until a set identifying an idle cord circuit is reached. When this occurs a testing circuit is completed from battery through the contacts of key 306 (this key is closed while the operator is at her position), outer left back contacts of relays 311, 310 and 309 in series, inner left back contact of relay 309, winding of 80 said relay, right contacts of key 317 individual to the cord circuit, conductor 351, inner back contact of relay 332, left back contact of relay 331, conductor 184, brush 162, inner right contact of relay 158, back contact of relay 152, right-hand winding of relay 130, lower contact 129 (6), inner left back contact of relay 132, lower right contact 128 (3+16), to ground. Relay 130 85 operates in the circuit traced and modifies the circuit so that it now leads through the left-hand winding and contact of said relay, right-hand winding of relay 101, lower left-hand contact 128 (3+17), to ground. The relay 101, however, is shunted by a parallel 90 path through the lower right contact 109 (6), brush 191, commutator segment 127, to ground until the brushes of the cord selector switch 180 are accurately centered upon the 95 terminals of the selected cord. When these brushes are accurately centered the brush 191 disengages the segment 127 removing the shunt and permitting the relay 101 to 100 energize in series with the left-hand winding of relay 130. Relay 101 completes a circuit from ground through its front contact, upper right contact 122 (6), winding of sequence switch 100 to battery. Sequence switch 100 leaves position 6 and moves into 105 position 8.

In position 8 the circuit previously traced through the left-hand winding of relay 130 and the right-hand winding of relay 101 is altered so that it now leads through the upper left contact 109 (8+11), and thence through the right-hand winding of relay 101 to ground at the lower left contact 128 (3+17). This shunt circuit around the winding of relay 130 permits this latter relay to become deenergized so that only the relay 101 remains in series with the relay 115 309 individual to the cord circuit.

The relays 309, 310 and 311 are three of a plurality of relays, the others not being 120 shown. These relays are individual respec-

tively to the several cord circuits at the operator's position served by the cord selector switch 180. They are arranged in serial relation with one another in such fashion that the testing circuit when closed through one of them, upon the selection of the corresponding cord, causes the energization of such relay whereby the remaining relays cannot be operated and consequently the corresponding cord circuits cannot be selected by the switch 180 or an equivalent switch. At the time the testing circuit is closed through the winding of relay 309, individual to the cord circuit shown in the figure, this relay becomes energized and attracts its armatures. Upon the energization of relay 309 the circuit is modified so that it now leads from battery through the closed contacts of key 306, thence through the outer left back contacts of all other relays in the series, such as relays 311, 310, etc., outer left armature and front contact of relay 309, winding of said relay, right contacts of key 317, conductor 351, and thence as traced through the winding of relay 101 to ground. Relay 309, at its outer back contact, opens the series circuit whereby none of the other relays individual to cord circuits can be operated, thus preventing the selection of another cord circuit until after relay 309 becomes deenergized to restore the closed condition of the series circuit. Relay 309 also completes a circuit from ground through the winding of the common relay 325, lamp 330, inner left front contact of relay 309, outer left front contact of said relay, through the outer left back contacts of relays 310, 311, etc. in series, to battery through the contacts of key 306. Relay 325 operates and closes a circuit for the pilot lamp 326. Moreover, the lamp 330 is lighted, which lamp is individual to the cord circuit and notifies the operator which one of the cords has been chosen for the extension of a connection. The operator seeing the common pilot lamp 326 burning knows that a call is coming to her position and upon seeing the individual lamp 330 illuminated is apprised of the particular cord that she is to take for use in extending the waiting call.

The common relay 325, in addition to closing a circuit for the pilot lamp 326, also establishes a circuit from ground through its left contact through the resistance 343, thence to the right-hand armatures of all relays 311, 310, 309, etc., individual to the group of cord circuits selectable by the cord selector switch 380. The back contacts of these armatures are connected to the terminals of the operator's cord finding switch 360. The back contact at the right-hand armature of relay 309 is shown as connected by way of conductor 352 with the terminal 353 in the cord finding switch 360. In a similar manner the back contact of relay 310

would be connected to the corresponding terminal 353 of the next set of terminals, the back contact at the right-hand armature of relay 311 connected to the corresponding terminal of a third set in the switch 360, and so on. Immediately that the relay 325 is operated, assuming that the brushes of the switch 360 are standing on the set of terminals representing some cord circuit other than the one shown in the figure, a circuit is closed from ground through the left contact of relay 325, resistance 343, right armature and back contact of relay 311, for example, thence through the contact in the switch 360 corresponding to relay 311, thence over the 75 cooperating brush 354, inner left back contact of relay 302, winding of relay 303 to battery. Relay 303 operates and closes a circuit from battery through its front contact through the contact and winding of the 80 stepping magnet 305 to ground. Stepping magnet 305 interrupts its own circuit and advances the brushes of the cord finder switch to the next set of terminals. If this next set of terminals represents a cord circuit other than the one in which the incoming call appears, then the relay 303 remains energized over a circuit through brush 354 and a grounded terminal 353, and the stepping magnet 305 advances the brushes another 85 step forward. This continues until the brushes of the switch 360 are advanced to the terminals representing the cord circuit shown in the drawing, at which time no ground potential will occur on the terminal 90 100 105 110 115 120 125 130 135 140 145 150 155 160 165 170 175 180 185 190 195 198 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

The relay 303, on releasing its armature, closes a circuit from battery through its back contact, contact of relay 313, winding of relay 301, outer back contact of relay 302, to ground at the left contact of relay 325. Relay 301 is operated in this circuit and closes the talking conductors 181 and 182 through to the operator's talking set indicated diagrammatically by the character 115 340. The operator now converses with the calling subscriber and ascertains the nature of his wants. Upon learning the connection desired she seizes the plug 334 of the cord circuit and inserts it in the proper jack 350. Previous to completing the circuit over the jack 350, the operator may communicate with a distant operator for the purpose of requesting the assignment of a trunk provided the system is one where this class of connections is involved. An order wire 341 of the well-known type is shown by means of which the operator may communicate with the distant operator.

It will be noted that while the operator is

5 talking with the calling subscriber current is supplied through the right-hand winding of the repeating coil 150 through the winding of the supervisory relay 152. In case this 5 relay energizes it opens the original circuit for holding the relay 101 energized in series with the individual relay 309. However, a substitute circuit is provided to meet this contingency and may be traced by way of 10 conductor 184, in the manner previously described, then over brush 162, inner right contact of relay 158, conductor 192, right contact 131 (8), right-hand winding of relay 101, lower left contact 128 (3+17) to ground. This circuit being independent of the contact of relay 152 insures that relay 101 remains energized while the operator is 15 communicating with the calling subscriber.

Upon inserting the plug 334 in the jack 20 350, a circuit is closed from battery through the winding of relay 332, sleeve of plug 334, sleeve of jack 350 to ground. As soon as relay 332 is operated it opens the circuit of relay 101 and relay 309. Relay 309 restores 25 and reestablishes the series circuit including the other individual relays whereby one of the other cord circuits in this group may be selected by a switch similar to the cord selector switch 180. Relay 309 opens the circuit 30 of the common relay 325 which becomes de-energized and the individual lamp 330 is darkened. A new circuit is closed for the relay 101 as follows: battery, through the winding of relay 331, inner front contact of 35 relay 332, left back contact of relay 331, conductor 184, thence by way of brush 162, inner right contact of relay 158, back contact of relay 152, upper left contact 109 (8+11), right-hand winding of relay 101, 40 lower left contact 128 (3+17) to ground. Relay 331 operates in this circuit but its resistance is so high that the relay 101 becomes deenergized. A circuit in parallel with this one also leads through the make-before-break contact 114 and the winding of relay 113 to ground. Relay 113, however, being shunted does not operate. The left back 45 contact of relay 331 is so designed that it maintains engagement with the armature until after said armature has made engagement with its front contact. Therefore, relay 331, upon energizing, completes a circuit from battery through its winding and left front contact, thence over conductor 184 50 as traced, to ground whereby the relay 331 is maintained energized independently of the relay 332.

Relay 332 also completes a circuit from ground through the contact 324 of the common sequence switch 300 which is closed in either positions 1, 3 or 5, provided the operator is at her position, conductor 355, left front contact of relay 332, lamp 328, conductor 183, left contact 136 (8+11), inner 55 right contact of relay 132, winding of relay

158 to battery. This circuit through the lamp 328, although closed as soon as the operator plugs in, remains shunted by means of the circuit previously traced through the winding of relay 158, and thence to ground at the contact 128 until the sequence switch 100 advances beyond position 11. Consequently, the lamp 328, which is the calling subscriber's supervisory lamp, remains dark. 70

The relay 331, upon operating, closes a circuit for the lamp 329 which illuminates and remains illuminated until the called subscriber answers. Relay 101, which becomes deenergized when included in series with the high resistance relay 331, completes a circuit 75 from ground through its back contact, upper right contact 119 (8), winding of sequence switch magnet 100 to battery driving said sequence switch out of position 8 and into position 9. In positions 9 and 10 a circuit 80 is closed from battery through the winding of sequence switch magnet 100, lower right contact 177, key 193 to ground. Sequence switch 100 thereupon moves out of position 9 through position 10 and into position 11, 85 which is the talking position.

After the connection has been extended to the called line and ringing current applied in the usual manner, the called subscriber answers by removing his receiver from the switchhook. As soon as the called subscriber responds a circuit is closed from battery through the lower right winding of repeating coil 150, winding of supervisory relay 152, upper contact 153 (10+11), inner 90 left front contact of relay 158, brush 160, conductor 182, ring of plug 334, thence over the loop of the outgoing line through the subscriber's substation or through equipment at an operator's position, dependent upon the 95 manner in which the connection is completed beyond, and returning over the tip of the plug 334, conductor 181, brush 159, outer left contact of relay 158, left-hand contact 156 (10+11), upper right-hand 100 winding of repeating coil 150 to ground. Relay 152 operates and opens the circuit previously traced through the winding of relay 331, and thence through the right-hand 105 winding of relay 101 to ground. There remains, however, the branch circuit including the winding of relay 331 and the winding of relay 113. The relay 113 does not receive sufficient current in series with the winding of relay 331 to operate even when 110 the shunt is removed. Moreover the resistance of relay 113 is also sufficiently high to permit the deenergization of relay 331. Relay 331 becomes deenergized and opens the circuit of the called supervisory lamp 115 120 329 notifying the operator that the called subscriber has responded.

When conversation has been completed the calling and called subscribers replace their receivers on the switchhooks and the 125 130

supervisory relays 145 and 152 become de-energized. The retraction of relay 145 opens one of the parallel circuits including the relay 158 which has already been traced. Relay 140 now operates from battery through the winding of relay 158, right inner contact of relay 132, conductor 189, left back contact of relay 145, normal contacts of relay 140 and right hand winding thereof, upper right contact 128 (9+11), to ground. Relay 140 also locks to the same ground through its right armature and front contact. Interrupted ground is connected to the left hand winding, left armature and front contact of relay 140 for purposes hereafter described. The release of relay 145 leaves relay 158 included remaining in the remaining circuit which, as above explained, leads over the conductor 183 through the supervisory lamp 328, and thence to ground at sequence switch contact 324. The resistance of the right winding of relay 140 being large the shunt has thus been removed from lamp 328 and this lamp becomes illuminated, notifying the operator that the calling subscriber has replaced his receiver on the switchhook. The calling subscriber may regain the attention of the operator by operating the switchhook, which causes the re-operation of relay 145 and connects interrupted ground through the left hand winding of relay 140 and left front contact of relay 145, thence to conductor 183 to cause lamp 328 to flash as a recall signal to the operator. The relay 152, in retracting its armature, reestablishes the circuit including the winding of relay 331 and the right-hand winding of relay 101 in shunt of the high resistance winding of relay 113. The decrease in resistance in series with relay 331 permits the flow of sufficient current to cause the operation of this latter relay, which, in turn, causes the illumination of lamp 329, apprising the operator that the called subscriber has also retired from the connection. On seeing both lamps glowing the operator withdraws the plug 334 from the jack 350.

The removal of the plug from the jack first results in the deenergization of the sleeve relay 332. The deenergization of relay 332 severs the circuit of the lamp 328 and this lamp becomes extinguished. The opening of the circuit of lamp 328 at the same time causes the deenergization of relay 158. The relay 158 is at this time included in series with the right-hand winding of relay 140 but the resistance of relay 140 is too great to permit relay 158 to retain its armatures. Relay 158, upon deenergizing, closes a circuit from ground through its outer right back contact, upper right contact 177 (11), winding of sequence switch magnet 100 to battery, driving said sequence switch out of position 11 and into position 12. In position 12 of the sequence switch a circuit is closed from battery through the winding of relay 158, inner right contact of relay 132, right contact 136 (12+16), resistance 137, interrupter 138 to ground. As soon as the interrupter 138 closes relay 158 operates and completes a circuit from ground through its outer right front contact, upper left contact 177 (12+16), winding of sequence switch magnet 100 to battery. Sequence switch 100 moves out of position 12 and into position 13. As soon as the interrupter 138 again closes after sequence switch 100 arrives in position 13, the circuit of relay 158 is reestablished and the sequence switch 100 is driven into position 14.

During the interval that the sequence switch 100 is passing from position 12 into position 14, as determined by the interrupter 138, the operation of the calling subscriber's message register 175 occurs in case the call was such as to require registration. The relay 113 will not have been deenergized due to the reasons explained. While the sequence switch 100 is moving from position 11½ to position 13½, a circuit is established from the source of metering current 174, left back contact of relay 113, lower left contact 133 (11½+13½), left back contact of relay 132, conductor 188, brush 151, terminal 151', inner left contact of relay 112, thence through the winding of the message register magnet 175 to the opposite pole of battery and ground. The accumulative effect of the two batteries is to operate the message register 175 making a charge against the calling line 100 501.

As soon after the sequence switch 100 reaches position 14 as the interrupter 138 closes, relay 158 becomes energized and establishes the above traced circuit for driving sequence switch 100 out of position 14 through positions 15 and 16 and into position 17. In this latter position the brush carriage of the line finder switch 190 is returned to its normal position by means of a circuit from battery through the winding of the power magnet 121, lower left contact 119 (17) back contact of relay 101 to ground. When the brush carriage is fully restored a circuit is established from ground through the lower left contact 128 (3+17), right-hand winding of relay 101, lower left contact 109 (17), brush 187, home contact 171, lower right contact 116 (17) to battery. Relay 101 operates, opens the circuit of the power magnet 121 and closes a circuit as follows: ground, through the front contact of said relay, upper right contact 122 (14+17), winding of sequence switch magnet 100 to battery. Sequence switch 100 moves out of position 17 and into position 18. Here a circuit is established from battery through the winding of the trip spindle power magnet 102, lower right contact 107 (18), upper right contact 107 (18+1), closed contacts 130

104 and 103 to ground. The trip spindle is rotated to its normal position at which time the contact 103 enters a deep notch and breaks engagement with the contact 104. 5 This opens the circuit of the power magnet 102 and the trip spindle ceases to rotate. While the trip spindle was being restored a circuit was maintained for relay 101 as follows: ground, through the contacts 103 and 104, upper right contact 108 (18), right-hand winding of relay 101, left-hand winding of said relay, lower left contact 116 (18), resistance 117 to battery. As soon as the trip spindle is restored and contacts 103 and 15 104 are opened, relay 101 becomes deenergized and completes a circuit as follows: ground, through the back contact of relay 101, upper right contact of relay 119 (18), winding of sequence switch magnet 100 to 20 battery. Sequence switch 100 thereupon restores to its normal position, position 1.

Consider now that the call being extended is one which should not be accompanied by an operation of the subscriber's message register 175. To prevent the actuation of the call meter the operator operates her key 336 slightly prior to withdrawing the plug 334 from the jack 350. At this time the sequence switch 100 is in the talking position, position 11. The operation of key 336 completes a circuit from ground through the winding of common relay 335, right contacts of key 336, conductor 182, brush 160, inner left contact of relay 158, upper contact 153 (10+11), winding of relay 152, lower right-hand winding of repeating coil 150 to battery. Relay 152 operates and removes the shunt from around the winding of relay 113, whereby this relay is included directly in series with the winding of relay 331. However, as previously explained, the resistance of relay 331 is too great to permit the operation of relay 113. In addition to the first circuit a further circuit is closed by the operation of the operator's key 336 and may be traced as follows: battery, through the resistance 338, contact of relay 337, intermediate contacts of key 336, inner front contact of relay 332, left back contact of relay 50 331, conductor 184, and thence through the winding of relay 113. Relay 337 also has its circuit closed at the same time but this relay, being slow to operate, does not attract its armature until after the circuit through its back contact has had time to perform its required function. The parallel circuits thus formed through the winding of relay 113 permit sufficient current to flow for causing the energization thereof. Relay 113, on operating, immediately locks in a circuit from ground through its winding and right front contact, upper right contact 116 (8+16), resistance 117 to battery. 55

Later, when restoration is taking place and the sequence switch 100 moves from po-

sitions 11½ and 13½ in a manner fully explained hereinbefore, the circuit for the operation of the meter 175 is maintained opened at the left back contact of relay 113. Hence, the release of the switches takes place 70 without any effect upon the subscriber's meter and the call is not charged against his line.

Another condition to be assumed is one where the nature of the connection being 75 extended is such that it is desirable to enter a double charge against the calling subscriber. In order to accomplish this the operator depresses the key 336 somewhat in advance to inserting the plug in the jack. At this time it will be recalled the sequence switch 100 is standing in position 8. The operation of the key 336, under these circumstances, causes the closure of the circuit previously traced through the winding of 85 relay 335 and the winding of the supervisory relay 152. Relay 152 in operating prepares a circuit from battery through the left-hand winding of relay 115, right contact 142 (8), front contact of relay 152, upper left contact 109 (8+11), right-hand winding of relay 101, lower left contact 128 (3+17) to ground. Relay 115 operates and locks in a circuit from ground through its right front contact and right-hand armature, 90 upper right contact 116 (8+16), resistance 117 to battery.

After the conversation has been completed and the operator initiates release of the mechanism, the sequence switch 100, on passing from position 11½ to position 13½, 100 closes the regular circuit for causing the operation of the message register 175, which was previously traced. Considering this circuit again it may be followed from the 105 source of metering battery 174, left back contact of relay 113, lower left contact 133 (11½+13½), the outer left contact of relay 132, conductor 188, brush 151, terminal 151', and thence through the winding of the message register 175 to battery. The closure of this circuit causes the operation of register 175. Shortly thereafter the sequence switch 100 passes from position 15½ to position 11. While moving through these positions 110 the metering circuit is closed a second time as follows: battery 174, left back contact of relay 113, left contact of relay 115, lower right contact 133 (15½+16), and thence over the circuit previously traced through 115 the winding of the message register magnet 175.

It will now be explained how the line 120 finder switches of the A and B groups are allotted for use. It will be recalled that the sequence switch 100 of the switch unit shown in Fig. 1 moved out of position 2 and into position 3 following the brush selection operation of the finder switch 190. At this time a new finder switch of the A group 125

should be allotted for use in connection with subsequent calls and this is done in the manner now about to be described. With the sequence switch 100 in position 3 a circuit 5 is closed from ground through the contact 164 (3-18), conductor 266, the lower right contact 233 (1) of the allotter switch 201, right contact of relay 207, and thence in parallel through the windings of the magnet of 10 switch 201 and relay 223 to battery. The allotter 201 moves out of position 1 and into position 2 where it makes a test of the condition of the next switching unit of the A group. If this unit is busy a contact similar 15 to the contact 164 will be in some position from 3 to 18 and hence a circuit identical with the one just traced is closed for advancing the allotter 201 out of position 2 and into position 3. This testing operation 20 continues until the allotter 201 reaches some position corresponding to an idle finder switch, at which time it comes to rest thereby allotting that finder switch for use. The relay 223, which operates in parallel with 25 the allotter 201, serves to hold open the circuit of relay 209, thereby preventing an incoming call from completing the fundamental circuit until the allotment is completed.

The allotter 200, which acts to allot the 30 finder switches of the B group, operates in precisely the same manner and need not be further described.

Initiation of a call in the B group of lines when one of the B finder switches is idle.—Should, for example, the subscriber of line 508, which belongs in the B group of 35 100, initiate a call at a time when some one of the B finder switches is idle, the allotted B switch is set in operation to select 40 the calling line in a manner analogous to that explained in connection with the previous call.

There is shown at the left of Fig. 2 a plurality of line relays, and the relation of 45 these with respect to the A and B groups and also with respect to the levels of the finder switch bank will now be considered. The relays 203 and 203' in the vertical row at the right are those of two lines of the A 50 group which occur in the first level of the finder switches. The two relays below the horizontal line CD in this vertical row are the corresponding line relays of two lines in the B group of 100, which likewise occur in the first level of the switches. The relays 55 204 and 204' in the next vertical row are the relays of two lines of the A group which occur in the second level of the switches, while the two relays immediately 60 below are those corresponding to two lines in the B set or group and appearing in the second level of the switches. Similarly, the relays 205 and 205' are the relays belonging to two lines in the A group which appear 65 in the third level of the finder switches.

These, for example, may be the relays of lines 500 and 501 diagrammatically illustrated in Fig. 5. The relays below the broken line CD in the same vertical row are those belonging to two corresponding lines 70 in the B group appearing in the third level of the switches, such as, for example, the lines 508 and 509.

When, therefore, the subscriber of line 508 initiates a call he causes the energization of 75 the line relay 267. Relay 267, in addition to placing a selectable potential on the test terminals in the bank of A and B finder switches, completes a circuit from battery through the make-before-break contacts of 80 relays 214, 215, 216, etc., thence through the winding of relay 216, as previously traced, winding of relay 212, conductor 252, key 253, left contact of relay 267, key 268, left contact of relay 222, winding of relay 208, 85 left back contact of relay 209 to ground. Relay 216 operates and prepares a circuit for itself over its front contact and at the same time closes a circuit for the relays 219 and 221. Relay 208 operates and opens the 90 operating circuit of relay 209 to prevent the actuation of this relay in case a subscriber in the A group initiates a call. Relay 208 also closes the fundamental circuit as follows:

95 ground, through the right contact of relay 212, conductor 257, contact of relay 258, winding of stepping relay 218, right contact of relay 208, outer left back contact of relay 206, right contact of relay 222, lower right contact 269 (1), conductor 270, thence to a contact similar to contact 108 of the allotted finder switch of the B group, and through the winding of a relay similar to relay 101. The allotted B finder switch is 100 started in operation, the proper set of brushes 105 is selected and tripped, and the switch is advanced in its hunting movement to select the terminals of the calling subscriber's line 108 in the third level. This procedure all 110 takes place in the same manner as that explained in connection with the previous call.

When the operated B finder switch has completed its brush tripping operation and its sequence switch 100 moves into position 2, the allotter switch 200 is advanced, and 115 a new unit is allotted for operation to handle subsequent calls occurring in the B group. Moreover, the relays 208, 212 and 216 are deenergized when the line is found as a result of the operation of the cut-off relay and these relays, upon restoring, place the common apparatus in condition for the receipt of subsequent connections either in the same or other groups of lines.

Initiation of a call on a line in the A group when all of the finders of the A group are busy.—Should the subscriber of line 501 of the A group originate a call at a time when all finders of the A group, which normally 120 serve these lines as first choice, are busy, 130

then a finder in the B group, if one be idle, is taken for use to serve the calling line. Assume that the subscriber 501 initiates a call causing the energization of line relay 5 205, of relays 216, 212 and also the energization of relay 209. Since all of the finders of the A group are busy the contacts 163, 163', 163'', etc. of the sequence switches, individual respectively to these finders, are in 10 some position between 3 and 18. Consequently, a series circuit is closed through all of these contacts from ground by way of conductor 271, the winding of relay 207 to battery. The relay 207 operates and remains 15 energized as long as the simultaneous busy condition of all switches of the A group prevails. Relay 207 being energized the fundamental circuit is closed as follows when the relay 209 operates in response to the initiation 20 of a call under the conditions assumed: ground, through the right contact of relay 212, conductor 257, contact of relay 258, winding of relay 218, right contact of relay 209, outer left front contact of relay 207, 25 right contact of relay 222, lower right contact 269 (1), conductor 270, and thence through the winding of a relay 201 of the allotted idle B finder switch. It will be seen that if all of the A finders are busy when a 30 call occurs in the A group, the fundamental circuit instead of extending to an A finder is directed as just traced over the front contact of relay 207, and thence to one of the B finder switches. The relay 207, which is 35 initially energized over the series circuit including contacts 163, 163' and 163'', is not permitted to deenergize when one of the A finder switches becomes idle at a time when the fundamental circuit is being extended 40 through to one of the B switches. This safeguard is provided by a circuit which leads from battery through the winding of relay 207, inner left contact of said relay, left front contact of relay 209 to ground. 45 Thus, it is seen how the fundamental controlling circuit, which controls the brush selecting operation of the finder switches in accordance with the registration set up on the register relays as a result of the initiation 50 of a call in either the A or B group of lines, is normally extended to the allotted finder switch of the group which normally serves as first choice the calling line. However, if all of these switches are busy then 55 the fundamental circuit is extended to the allotted finder switch of the other group normally serving the calling line as second choice, provided, of course, there is at the time such an idle switch in the second choice 60 group of switches.

When the operator leaves her position she opens the key 306 thus permitting relay 307 to release. Relay 307 closes a circuit for driving sequence switch 300 into either position 2, 4 or 6, opening contact 324. The

opening of contact 324 opens an obvious circuit which maintains relay 225 energized as long as the operator is at her position. The release of relay 225 closes a circuit for driving sequence switch 220 into one of its even 70 positions. The sequence switch 220 in its even positions places a ground through contacts 227, 228, 229, 231, etc., on the contacts of the alloters 200 and 201 with respect to all positions in which allotment is made 75 of finder units having access to the said operator's position. Hence when an operator is away from her position the alloters will not allot a switch having access to cords at such position. 80

What is claimed is:

1. In a telephone system, a plurality of lines divided into a plurality of groups, automatic switches arranged in a plurality of groups, each group of switches serving a different group of lines as first choice, means for allowing each group of switches to serve other lines as second choice, means for operating a switch in any of said groups to select and extend one of said lines, and means variably operable in accordance with the operation of said switch for controlling said switch directly. 85

2. In a telephone system, a plurality of lines divided into a plurality of groups, automatic switches arranged in a plurality of groups, each group of switches serving a different group of lines as first choice, means for allowing each group of switches to serve other lines as second choice, means responsive to a call on one of said lines for operating any one of said switches to select and extend such lines, and means variably operable in accordance with the movement of said switch for controlling said switch directly. 90

3. In a telephone system, a plurality of lines divided into a plurality of groups, automatic switches each having a terminal bank, said lines appearing in the terminals of said switches and divided into a plurality of sub-groups, said switches arranged in a plurality of groups, each group of switches serving a different group of lines as first choice, means for allowing each group of switches to serve other lines as second choice, means for directly operating a switch in any group to a variable extent in accordance with the sub-group of lines to be selected, and means for controlling the further operation of said switch to select one of said lines. 110

4. In a telephone system, a plurality of lines divided into a plurality of groups, automatic switches each having a terminal bank, said lines appearing in the terminals of said switches and divided into a plurality of levels, brushes for each level of lines at each switch, said switches arranged in a plurality of groups, each group of switches 115 120 125 130

- 5 serving a different group of lines as first choice, means for allowing each group of switches to serve other lines as second choice, means for directly moving a switch in any group to select the brushes having access to a given level of lines, said directive movement varying in accordance with the brushes to be selected, and means for controlling the operation of said brushes to select one of said lines.
- 10 5. In a telephone system, a plurality of lines divided into a plurality of groups, automatic switches arranged in a plurality of groups, each group of switches serving a different group of lines as first choice, means for allowing each group of switches to serve other lines as second choice, means comprising a counting device for directly operating a switch in any of said groups to select a portion of said lines, and means for controlling said switch in a hunting movement to select and extend a particular one of said lines.
- 15 6. In a telephone system, a plurality of lines divided into two groups, a plurality of automatic switches arranged into two groups, each group of switches serving respectively one group of lines as first choice and the other group of lines as second choice, means comprising a counting device for operating a switch in either of said groups to select and extend one of said lines, and means for controlling the operation of said switch directly.
- 20 7. In a telephone system, a plurality of lines divided into a plurality of groups, automatic switches arranged in a plurality of groups each group of switches serving a different group of lines as first choice, means for allowing each group of switches to serve other lines as second choice, a counting device common to said switches, means for operating a switch in any group, the operation of said switch causing said device to function to determine one extent of movement of said switch, and means for determining another extent of movement of said switch independently of said counting device.
- 25 8. In a telephone system, a plurality of lines arranged in a plurality of groups, automatic switches arranged in a plurality of groups, each group of switches serving a different group of lines as first choice, means for allowing each group of switches to serve other lines as second choice, means for establishing a registration of the identity of any one of said lines, a counting device common to said switches, means under control of said counting device for operating a switch in any group to select a portion of said lines, and means for operating said switch independently of said device to select a particular line in said selected portion of lines.
- 30 9. In a telephone system, a plurality of lines arranged in a plurality of groups, automatic switches arranged in a plurality of groups, each group of switches serving a different group of lines as first choice, means for allowing each group of switches to serve other lines as second choice, means responsive to the initiation of a call on one of said lines for establishing a registration of the identity of said line, a counting device common to said switches positioned in accordance with the established registration, means under control of said device for operating a switch in any group to select a portion of said lines, and means for operating said switch independently of said device to select a particular line in said selected portion of lines.
- 35 10. In a telephone system, a plurality of subscribers' lines divided into two groups, automatic switches arranged in two different groups, each group of switches arranged to serve one of said groups of lines respectively as first choice, and the other group of lines as second choice, registers for taking a registration of the identity of a calling subscriber's line, a variably operable counting device, means for operating a switch to select and extend the calling line, and means under control of said registration and said counting device for determining the extent of movement of said switch.
- 40 11. In a telephone system, subscribers' lines arranged in two groups a plurality of automatic switches arranged in two groups, each group of switches serving respectively one of said groups of lines as first choice and the other group of lines as second choice, registers for taking a registration of the identity of a calling subscriber's line, means for operating a switch to select and extend the calling line, a variably operable set of counting relays for determining the extent of operation of said switch, and means dependent on the setting said registers for determining the operation of said counting relays.
- 45 12. In a telephone system, a plurality of lines divided into a plurality of groups, automatic switches arranged in a plurality of groups, each group of switches serving a different group of lines as first choice and serving another group of lines as second choice, line designation registering means, a variably operable counting device set in accordance with said registering means, means for operating normally a switch in the group serving a given line as first choice, the operation of said switch causing said counting device to determine the extent of movement of said switch, means for operating a switch in another group when all switches serving such line as first choice are busy, and means for determining the extent

of movement of said switches independently of said counting device.

13. In a telephone system, a plurality of lines divided into groups, automatic switches arranged in a plurality of groups, each group of switches serving a different group of lines as first choice, and serving another group of lines as second choice, means for operating normally a switch in the group serving a given line as first choice to select and extend such line; means for operating a switch in another group when all switches serving such line as first choice are busy, a register mechanism for taking a registration of said lines, sets of counting relays positioned in accordance with an established registration and means for controlling the operation of any of said switches in accordance with the operation of the counting relays.
14. In a telephone system, a plurality of lines divided into two groups, automatic switches arranged in two groups, each group of switches serving respectively one of said groups of lines as first choice and the other group of lines as second choice, means for allotting an idle switch in either group for use, a variably operable counting device for said switches, means for setting said device in accordance with a line designation, means for operating one of said switches, said switch while operating cooperating with

said counting device to determine the extent of movement of said switch.

15. In a telephone system, a plurality of lines divided into a plurality of groups, automatic switches arranged in a plurality of groups, each group of switches serving a different group of lines as first choice, means for allowing each group of switches to serve other lines as second choice, means for operating a switch in any group to select a portion of said lines, and means for reoperating said switch to seize a particular line in said selected portion.

16. In a telephone system, a plurality of lines divided into a plurality of groups, automatic switches arranged in a plurality of groups, each group of switches serving one group of lines as first choice, and another group of lines as second choice, means responsive to the initiation of a call on any line for establishing a record of the designation thereof, means under control of said established record for operating said switch to select the portion of said lines wherein the calling line is located, and means for reoperating said switch independently of said record to seize said calling line.

In witness whereof, I hereunto subscribe my name this 3rd day of February A. D., 1922.

GERALD DEAKIN.
